UNITED STATES PATENT OFFICE.

ERNEST F. McCARTHY, OF WORCESTER, MASSACHUSETTS.

DESIGN FOR A LAMP-SUPPORT.

59,604.

Specification for Design.

Patented Nov. 8, 1921.

Application filed September 10, 1920. Serial No. 409,481. Term of patent 3½ years.

To all whom it may concern:

Be it known that I, ERNEST F. McCARTHY, a citizen of the United States, residing at Worcester, in the county of Worcester and State of Massachusetts, have invented a new, original, and ornamental Design for a Lamp-Support, of which the following is a specification, reference being had to the accompanying drawing, forming part of this specification, which is a front elevation of a lamp.

I claim:

The ornamental design for a lamp support, as shown.

In testimony whereof I have hereunto affixed my signature.

ERNEST F. McCARTHY
